UNITED STATES PATENT OFFICE.

GEORGE GUNTHER, OF LONG BEACH, CALIFORNIA.

DESIGN FOR A HUMIDIFIER.

Application filed April 29, 1925. Serial No. 13,258. Term of patent 14 years.

To all whom it may concern:

Be it known that I, GEORGE GUNTHER, a citizen of the United States, residing at Long Beach, in the county of Los Angeles and State of California, have invented a new, original, and ornamental Design for Humidifier, of which the following is a specification, reference being had to the accompanying drawing, forming part thereof.

The drawing is a view, in elevation, of a humidifier, showing my new design.

I claim:

The ornamental design for a humidifier substantially as shown.

GEORGE GUNTHER.
